UNITED STATES PATENT OFFICE.

ARTHUR W. WEED; OF BROOKLYN, NEW YORK.

BELT-FASTENER.

SPECIFICATION forming part of Letters Patent No. 256,259, dated April 11, 1882.

Application filed October 23, 1881. (No model.)

To all whom it may concern:

Be it known that I, ARTHUR W. WEED, of Brooklyn, in the county of Kings and State of New York, have invented certain new and useful Improvements in Belt-Fasteners, of which the following is a specification.

I construct a light frame, of tough metal, with holes in its edges, re-enforced or surrounded by sufficient metal to give ample strength at those points. I apply in these holes split pins of corresponding section, presenting a smoothly-rounded head on the face, which is to be outside, out of contact with the pulley, and presenting on the other face two parts of unequal length. These, being made of tough iron or other material adapted to clinch, are inserted through holes produced in corresponding positions at a proper distance from the abutting ends of the belt and the extreme ends spread apart or clinched.

The accompanying drawings form a part of this specification and represent what I consider the best means of carrying out the invention.

Figure 1 is an outer face view. Fig. 2 is a section on the line S S in Fig. 1. This shows two of the split pins spread and clinched. One is in the act of being set. It is inserted through the metal frame and through the material of the belt, but has not yet been spread or clinched. Fig. 3 is a section on the line T T in Fig. 1. Fig. 4 represents one of the split pins detached. Fig. 5 is a section, showing a modification.

Similar letters of reference indicate corresponding parts in all the figures.

A A are the adjacent ends of the belt, abutting squarely, as usual. An equal number of smooth round holes, equally spaced, are produced in each at a little distance from the end.

B B' is an open-work frame of malleable cast-iron or other suitable material. In each part B' is a central hole. The holes in the belt correspond in number and position with the re-enforces B'. The fastening is effected by split pins inserted through each.

I will use the letter D to indicate one of the split pins entire, the same letter, with additional marks, as D' D'', &c., being used to designate portions thereof when necessary.

D' is a smoothly-rounded head, adapted to lie on the outside of the re-enforce B'.

D² and D³ are the legs or split parts, the part D³ being something longer than the part D². This facilitates the spreading apart or clinching of the pin after it is inserted.

To fasten the ends of a belt, the places for the holes are marked by laying on the plate B and pricking through the holes, or by other suitable means, and the holes smoothly punched. Then, having drawn the ends together by the ordinary clamps or other suitable means, the frame B is placed in position and the split pins D successively inserted, and their ends D² and D³ spread apart and clinched down. The spreading may be effected by operating with an ordinary hammer by first striking an oblique blow on the longest part, D³, and then on the shorter part, D², which will be left exposed by the bending down of its longer associate. A suitable hammer or dolly being held against the head, and the split ends firmly clinched down for all the pins, the operation of fastening is complete.

When it is desired to remove a fastening the spread ends of D² D³ are closed together again, and the pin may be easily driven out.

The metallic frame B B' should have ample strength to resist the tensile pull to which it is subjected in the use of the belt. If the metal is properly-annealed iron, it will be able to take on a slight curvature, which facilitates its lying smoothly on the pulleys. The curvature may be impressed by any suitable means in its manufacture. The use of the belt-fastening will tend to impress a slight degree of curvature, even if none is intentionally introduced.

Modifications may be made in the forms and proportions. The fastener may be made for any width of belt. The parts B' and split pins D may be placed nearer together or farther apart within wide limits. They may be set "jogged"—that is to say, alternate pins may be set farther in on the belt than the intermediate ones. The openings in the frame B may be varied in form and proportions.

Parts of the invention may be used without the whole. I can realize some of the benefits of the invention with a continuous plate instead of the open-work frame B.

The parts D' may be made somewhat thicker than the remaining parts of the frame. In such case the increased thickness should lie on the outer face of the frame, away from the belt. I esteem it important that the parts D' shall be sufficient, either by increased thickness or by a considerable circular extension, to effectually re-enforce the hole in which the split pin is inserted.

I propose in some instances to attach the split pins permanently to the frame B. This can be effected by placing the pins, properly prepared, in a mold and pouring the melted metal for the frame B so that it flows around and unites with the heads or bends of the several pins.

Fig. 5 is a section through the junction of a split pin with the metal frame. I can employ the same form with the pins removable.

Instead of placing the split pin D so that the long and short parts when separated and clinched down shall extend transversely of the

belt, as shown, I can arrange them so that the bends shall extend longitudinally of the belt. Such arrangement may be preferable when it is to work on large pulleys.

I claim as my invention—

1. The open-work frame B and split pins D, combined and adapted to serve as herein specified.

2. The combination of two abutting lengths of belting, open-work metallic frame having re-enforced holes, and removable split pins inserted through the frame and through the belt and secured by clinching, as specified.

In testimony whereof I have hereunto set my hand, at New York city, this 26th day of October, 1881, in the presence of two subscribing witnesses.

ARTHUR W. WEED.
